ATTORNEYS.

UNITED STATES PATENT OFFICE.

CHARLES WHITNEY STEVENS, OF CHICAGO, ILLINOIS, ASSIGNOR TO STEVENS
PARTITION AND FLOOR DEADENER CO., OF CHICAGO, ILLINOIS, A CORPORA-
TION OF ILLINOIS.

CEILING CONSTRUCTION.

1,415,273.

Specification of Letters Patent.

Patented May 9, 1922.

Application filed March 9, 1917. Serial No. 153,878.

To all whom it may concern:

Be it known that I, CHARLES WHITNEY STEVENS, a citizen of the United States, residing at Chicago, in the county of Cook and State of Illinois, have invented new and useful Improvements in Ceiling Constructors, of which the following is a full, clear, concise, and exact description, reference being had to the accompanying drawing, forming a part of this specification.

My invention relates to a ceiling construction and, more specifically, to a ceiling construction which is supported on cushions.

One of the objects of my invention is to provide an improved ceiling construction which will prevent sound from being transmitted from the floor above, and which will permit the ceiling to adjust itself in case of shrinkage and settlement, thereby preventing cracking of the ceiling. Further objects will appear from the detailed description to follow and from the appended claims.

In the drawings, in which several embodiments of my invention are shown—

Fig. 1 is a perspective view showing a joist, part of the floor supported thereby, and the cushion supports for supporting the ceiling construction from the joists;

Fig. 2 is a vertical section showing the cushioning support and part of the joist;

Fig. 3 is a bottom view of a suspension member forming part of the ceiling support;

Fig. 4 shows an embodiment of my invention used in fireproof building construction, the view being a vertical section;

Fig. 5 is a perspective view of the pad-support shown in Fig. 4; and

Fig. 6 is a vertical section showing another embodiment of my invention used in fireproof construction.

Referring to the drawings in detail and first to the form of Figs. 1, 2 and 3, the building construction as shown comprises a horizontally-extending joist 10, a flooring 11 supported by said joist, a ceiling construction 12 underneath the joist 10, and a plurality of cushioning supports 13 for suspending the ceiling construction 12 from the joist 10.

The ceiling construction 12 comprises a plurality of stringers 14, to which the laths 15, which support the plaster 16, are secured.

The pad-supports 13 may be formed of sheet-metal having a vertical U-shaped portion 17 for engaging the side of the joist 10,

a horizontal rectangular portion 18 struck up from the U-shaped portion 17 for engaging the lower edge of the joist 10 for positioning the pad-supports, and a horizontal pad-rest portion 19 on which the pad 20 rests. The pad-supports may be provided with a vertical flange 21 to assist in holding the pad in position. For suspending the ceiling construction from the pads, each pad-holder is provided with a suspension-device 22, which comprises a U-shaped portion 23 for embracing the stringer 14, a shank-portion 24 extending up through an opening in the pad-rest, and a bearing-plate or washer 25 to which the upper end of the shank 24 is secured. The shank portion extends loosely through the opening in the pad-rest so as to be free to move with respect thereto. For holding the pad 20 and the suspension-member 22 in proper position with respect to the pad-supports 13, the suspension-member may be provided with a shoulder portion 26 for engagement with a fiber washer 27 located beneath the pad-supports. This fiber washer serves to hold the suspension-member in position with respect to the pad-supports, but due to the material of which the washer is composed, it does not readily transmit vibration.

The stringer 14 may be secured to the U-shaped portion 23 of the suspension-member by means of a nail 28 extending through the wide part 29 of the U-shaped portion.

In this construction there is no connection between the joist 10 and the ceiling construction, except through the cushioning pads 20. Because of this cushioned connection, sound will not be readily transmitted from the floor above to the ceiling construction. Also, because of the yielding connection, a shrinkage or settlement of the joists 10 and associated parts is not apt to cause the plaster of the ceiling construction to crack, as there is no rigid, unyielding connection between the joists and the ceiling construction.

In the form of my invention shown in Figs. 4 and 5, I have shown my invention in connection with a fireproof construction. In this construction the floor construction 105 comprises a horizontally-extending body portion of cement, or the like, indicated at 30, and the ceiling construction may comprise an expanded metal web 31 imbedded in the plaster 32, for supporting the plaster. The 110

cushion support may be formed of a single integral piece of sheet-metal shaped to form a U-shaped portion 33 for receiving and positioning the cushioning-pad 34, and an ear 35 having an aperture 36 to receive the hook 37, the shank 38 of which is secured to a horizontally-extending plate 39 imbedded in the cement 30. The expanded metal web 31 may be suspended from the cushioning supports by means of a suspension-member 40 having a head 41 at its lower end, on which the web 31 rests, and having a bearing-plate 42 at its upper end, which rests on the pad 34.

In this form as in the form of Figs. 1, 2 and 3, there is no connection between the floor construction and the ceiling construction except through the cushioning supports.

In the form of my invention shown in Fig. 6, it is shown in connection with a fireproof construction comprising a horizontally-extending floor construction 43, of cement or the like, in which are imbedded reinforcing steel members, such as the I-beams 44. The ceiling construction 32 may be the same as in the form of Fig. 4, as also the pad-support and suspension-member.

In this form, however, the aperture 36 of the ear 35 receives a hook 45, the shank of which extends over and is secured to the I-beam 44. In this construction, also, there is no connection between the floor construction and the ceiling construction except through the cushioning pads.

One of the functions of the fiber washer 27 is to hold the suspension device 22 against upward movement when the laths 15 are being nailed to the furring strips or stringers 14. After the plaster 16 has been applied, the ceiling construction may settle so that the washer 27 will be entirely out of contact with the horizontal pad rest portion 19.

I claim as new and desire to secure by Letters Patent:

1. A building construction comprising a horizontally-extending support, a ceiling construction therebeneath, and a plurality of cushioning supports for suspending said ceiling construction from said horizontal support, each cushioning support serving as a sound indicator to prevent the ready transmission of sound from the horizontally extending support to the ceiling, and also as a yielding ceiling support whereby the possibility of cracking of the ceiling plaster is minimized.

2. A building construction comprising a horizontally-extending support, a plurality of pad supports secured thereto, a plurality of pads bearing on said supports, respectively, and a ceiling construction underneath said horizontal support and supported by said pads, each pad serving as a sound insulator to prevent ready transmission of sound from the horizontally extending support to the

ceiling and also as a yielding ceiling support whereby the possibility of cracking of the ceiling plaster is minimized.

3. A building construction comprising a horizontally-extending support, a plurality of pad supports secured thereto, each comprising a horizontal supporting plate, a plurality of pads, one supported on each plate, and a ceiling construction underneath said horizontal support and supported by said pads, each pad serving as a sound insulator to prevent ready transmission of sound from the horizontally extending support to the ceiling and also as a yielding ceiling support whereby the possibility of cracking of the ceiling plaster is minimized.

4. A building construction comprising a horizontally-extending support, a plurality of pad supports secured thereto, each comprising a horizontal supporting plate, a plurality of pads, one supported on each plate, a ceiling construction underneath said pad supports, and means bearing on said pads for suspending said ceiling construction, each pad serving as a sound insulator to prevent the ready transmission of sound from the horizontally extending support to the ceiling, and also as a yielding ceiling support whereby the possibility of the cracking of the ceiling plaster is minimized.

5. A building construction comprising a horizontally-extending support, a plurality of pad supports secured thereto, each comprising a horizontal apertured supporting plate, a plurality of pads, one supported on each plate, a ceiling construction underneath said pad supports, and means for suspending said ceiling construction comprising a plurality of suspension members, one carried by each pad, each comprising a hook member, each supporting plate being apertured to receive a hook member, each pad serving as a sound insulator to prevent the ready transmission of sound from the horizontally extending support to the ceiling, and also as a yielding ceiling support whereby the possibility of cracking of the ceiling plaster is minimized.

6. A building construction comprising a horizontally-extending support, a hook member secured thereto, a pad-support having an apertured portion to receive said hook, a pad for said support, and a ceiling construction beneath said horizontal support supported by said pad, said pad serving as a sound insulator to prevent the ready transmission of sound from the horizontally extending support to the ceiling, and also as a yielding support whereby the possibility of cracking of the ceiling plaster is minimized.

In witness whereof, I have hereunto subscribed my name.

CHARLES WHITNEY STEVENS.
